UNITED STATES PATENT OFFICE.

WILLIAM SCHREIBER, OF PHILADELPHIA, PENNSYLVANIA.

GATE-LATCH.

1,226,120.

Specification of Letters Patent.

Patented May 15, 1917.

Application filed May 19, 1915. Serial No. 29,125.

To all whom it may concern:

Be it known that I, WILLIAM SCHREIBER, a citizen of the United States, residing at Philadelphia, in the county of Philadelphia, State of Pennsylvania, have invented certain new and useful Improvements in Gate-Latches; and I do hereby declare the following to be a full, clear, and exact description of the invention, such as will enable others skilled in the art to which it appertains, to make and use the same.

This invention relates to new and useful improvements in gate latches, and is particularly directed to the provision of means operable from either side of the gate for actuating the latch bar.

It is the object of the present invention to generally improve the structure and efficiency of latch devices of this character, and to so arrange the parts thereof that they will not be liable to be broken off, it being more specifically the object in this latter connection to provide handle members for actuating the latch bar which are readily removable and which when not in operation, may swing to lie against the gate.

With the above and other objects and advantages in view, the invention resides more particularly in the novel combination, formation and arrangement of parts more fully hereinafter described and particularly pointed out in the appended claim.

Reference is had to the accompanying drawings wherein similar characters of reference designate corresponding parts throughout the several views, and in which:

Figure 1 is a side elevation of the improved device attached to a gate,

Fig. 2 is a vertical sectional view taken through the operating bolt or shaft of the device,

Fig. 3 is a top plan view of the structure shown in Fig. 1, and

Fig. 4 is a perspective view of one of the handle members.

Referring now more particularly to the accompanying drawings, there is shown a gate 5 carrying the improved latch structure and a post 6 against which the gate is adapted to swing, a keeper 7 of conventional type being positioned on this post

and provided in its top with a notch 8 for receiving the latch bar, and having its forward edge beveled to provide a cam edge 9 leading thereto.

Journalized in a transverse bore 10 in the gate sill is an actuating shaft 11 having one end squared at 12 to engage in a squared opening 13 formed in the rear end of the latch bar 14, this bar extending outwardly of the gate sill to engage the keeper as in the usual manner. Secured to the gate at the ends of the bore 10 are circular plates 15 provided with openings receiving the ends of the shaft. Also secured to the gate at the latch bar side thereof and forwardly of the shaft is a guide plate 17 carrying a loop 18 slidably holding the bar. The bar is normally urged into downward or engaging position by a leaf spring 19 secured to the upper end of the guide plate and bearing thereon.

Detachably and pivotally mounted handles are provided for the ends of the shaft and each of these handles comprises a single length of stout wire having its intermediate portion and the portions adjacent thereto bent to form a grip 20 and having its end portions further bent and directed laterally from the intermediate portion of the grip to form a shank 21, these end portions being terminally bent to form eyes 22 adapted to lie at the sides of the shaft. Pins 23 are passed through these eyes and threadedly engage in the ends of the shaft to hold the handles in place; the handles being so positioned relative to the shaft that they may normally swing on these pins to lie against the gate, thus avoiding the possibility of their being struck and broken off, as with handles of a rigid type extending outwardly from the shaft.

Thus an exceedingly simple and efficient device has been provided, which may be readily associated with a gate for latching the same.

What is claimed is:

In a gate latch, the combination with a post carrying a keeper, a gate movable with relation thereto, a shaft mounted for rotation in said gate and having its ends transversely apertured, a latch bar fixed on said shaft and projecting into operative en-

gagement with said keeper, a spring carried on said latch bar and bearing below the upper end of the keeper for holding the latch bar at the limit of its downward movement, handles having looped ends spaced apart and alined with the ends of the aperture through the shaft and pins detachably inserted through the aperture

and the alined loops for supporting the handles.

In testimony whereof, I affix my signature, in the presence of two witnesses.

WILLIAM SCHREIBER.
